APPARATUS FOR STITCHING WELT SHOES

Joseph J. Goellner, St. Louis, Mo., assignor to
 Landis Machine Company, St. Louis, Mo., a
 corporation of Missouri

Application February 1, 1940, Serial No. 316,754

8 Claims. (Cl. 112—46)

The invention relates to the sewing of shoe soles and uppers together, and more particularly to the sewing of shoes in which the upper is turned outwardly towards the edge of the sole and a welt strip overlies the out-turned edge of the upper. Such shoes may be termed "stitch down" shoes.

Heretofore the operator, when completing a stitching operation, released the presser foot and removed the shoe from the machine, at the same time also drawing out a length of thread and a length of the welt strip. He then turned the shoe over, picked up a hand knife and cut the welt strip at the end of the stitching, and then pulled the welt strip supply back so as to retract the cut end of the strip to the needle before beginning another stitching operation.

The object of the present invention is to facilitate the severing of the welt strip at the end of a stitching operation. With the present invention, the manual release of the presser foot also actuates a clamp for the welt strip. Some types of welts may then be severed by a pull or jerk on the shoe, but, if preferred, the mechanism may include a knife to sever the welt strip at the needle before the shoe is removed from the machine. Such a severing eliminates waste of the welt strip and avoids the handling of a loose tool for cutting the welt strip and avoids the manual retracting of the drawn-out portion of the welt back to the needle and any adjustment of its end which may be required.

In the accompanying drawings illustrating a selected embodiment of the invention—

Figure 1 is a side view of the essential portions of a shoe stitcher and shows a shoe being stitched.

Figure 2 is a front elevation of the same parts. Figure 3 is a top view of the welt gripping device shown in Figure 2.

Figure 4 is a vertical longitudinal section through the device taken on the line 4—4 of Figure 3.

Figure 5 is a vertical transverse section of the device taken on the line 5—5 of Figure 4.

Figure 6 is a detail elevation of the work support, presser foot, knife bracket and its operating lever looking at the same from the right hand side of the machine; i. e., opposite from the direction of the view of Figure 1, and showing the parts drawn to an enlarged scale.

Figure 7 is a top view of the parts shown in Figure 6.

Figure 8 is a front elevation of the work support or needle plate and the welt severing knife, 55

Figure 9 is a detail vertical section taken on the line 9—9 of Figure 6.

The frame 1 of the machine head mounts brackets 2 in which is journalled the main cam shaft 3 carrying the cams 4 and 5 by which the needle and awl segments 7 and 8 respectively are actuated. The needle plate or work support 9 projects from the frame. The presser foot 6 may be released manually by a pull rod 10 connected to a foot treadle (not shown). All of the above parts are of the usual construction, except as to detail arrangement described below, and in themselves do not constitute the present invention.

15 A bracket 11 is secured to the machine head at the right hand side of the frame. A clamping jaw 12 is pivoted at 13 to bracket 11 and cooperates with the outer end 14 of the bracket to provide a clamp for the welt strip W which extends through the clamp and through a slot 15 (Fig. 8) in needle plate 9. Normally springs 16 thrust elements 12 and 14 apart, as shown in Figure 4. A screw 17 threaded through jaw 12 has its lower end disposed to seat on bracket 11 and 20 limit the anticlockwise movement of jaw 12. The outer end of jaw 12 is connected by a yielding linkage 18 to the presser foot release rod 10 whereby depression of the presser foot treadle to release the presser foot is accompanied by clamping of the welt strip between elements 12 and 14. When the welt strip is so clamped a jerk, or even a strong tug on the welt strip, as may be provided by pulling the shoe S from the machine, will tend to sever the welt strip at the needle plate where the welt strip has been pierced by the awl 19 during the last stitch forming operation.

25 The ease of severance of the welt strip will depend upon its thickness and material. If the 40 welt strip is thin or of relatively weak material, such as fiber or composition, the parts described will be ample for the intended purpose, but it may be preferred to provide a knife 20 (Figs. 6, 7 and 8) for cutting the welt strip if it is of 45 tougher material, such as leather, or if it is too thick to be readily severed by a pull on the shoe. Knife 20 is on an arm 21 carried by a bracket 22. The arm is positioned behind work support 9 and the knife extends forwardly to slide over the top of the work support and preferably is received in a groove 27 in the top of the work support. A shoe edge gauge bracket 22 is slidable forwardly and rearwardly by a crank shaft 23 journalled on the machine head and having an upper arm 24, connected to the bracket, and an

operating arm 25 terminating in a handle 26 which may be grasped by the operator to oscillate shaft 23 to advance or retract knife 20.

Ordinarily, the welt strip will only be severed when the presser foot treadle is depressed and the clamp has gripped the welt strip, but it will be understood that such gripping is not necessary if the knife-moving operation is performed. Nevertheless, it is preferred to use the clamp with the cutting mechanism to insure severance of the strip irrespective of an incomplete cut because of a dull knife.

It is obvious that the details of the structure may be varied in numerous ways without departing from the spirit of the invention and the exclusive use of such modifications of the described invention as come within the scope of the claims is contemplated.

I claim:

1. In a stitcher arranged for sewing a shoe upper, welt strip and sole and having a presser foot and mechanism for releasing the presser foot at the end of a stitching operation, a welt clamp, and a connection between said mechanism and said clamp for operating the latter.

2. In a shoe stitcher, a work support, a co-operating presser foot, a device arranged to receive a welt strip in its passage to the work support during the normal operation of the machine, said device including a clamp for the welt strip, a manually operable member for releasing said presser foot and a yielding connection between said device and member for actuating said clamp by operation of said member.

3. In a shoe stitcher including a needle and work support, a knife operable at will by the operator to sever a welt strip adjacent to said needle, and a device operable at will by the operator and independently of the knife to clamp the welt strip against movement to facilitate severance of the strip by the knife.

4. In a shoe stitcher including a needle, a work support adjacent to said needle and apertured to provide for passage therethrough of said needle and a welt strip, a device spaced from said work support and operable at will by the operator to clamp the welt strip against movement, and a knife movable at will by the operator across said work support to sever the welt strip where it emerges from said support.

5. A device for use on a shoe stitcher having a work support and a needle passing therethrough, comprising a bracket for attachment to the stitcher frame, a member pivoted to said bracket and spaced substantially from said work support, and manually operable means for moving said member toward said bracket to clamp a welt strip between them without severing the welt strip.

6. In a stitcher arranged for sewing a shoe upper, welt strip and sole, a stitcher head, a work support thereon having an aperture for a needle and an adjacent aperture for the welt strip, a knife movable over said work support to sever the welt strip, and a device for actuating said knife including a shoe edge gauge bracket supporting the knife and slidably mounted on said stitcher head and a lever pivotally mounted on the front of said stitcher head and having one end connected to said bracket.

7. In a shoe stitcher having a needle and a stationary work support plate provided with an aperture through which said needle may pass and provided with an adjacent aperture through which a welt strip may be passed as it travels towards the work, a presser foot for clamping the work, including a welt strip, against said support plate, a device spaced from said support plate and operable manually at will to clamp the welt strip before it reaches said support plate so that the welt strip is held against movement through the aperture therefor in the support plate whereby the strip may be severed adjacent to the needle by pulling or jerking the strip against the edge of the aperture therefor in the support plate.

8. A device for use on a shoe stitcher having a frame and a work table and a presser foot and a needle associated therewith and a foot treadle operated rod for releasing the presser foot when the rod is depressed, the device comprising a bracket for attachment to the stitcher frame, a member movable on said bracket, said bracket and member including opposing jaws, and means for connecting said member to the stitcher control foot treadle rod to move said jaws towards each other when the treadle rod is depressed, said jaws being arranged to receive a welt strip between them on its way to the work table and to clamp the welt strip against movement when the foot treadle rod is depressed.

JOSEPH J. GOELLNER.
